Primary Examiner — Eliza Z Bennett-Hattan(74) *Attorney, Agent, or Firm* — EIP US LLP(57) **CLAIM**

We claim the ornamental design for a fastening device, as shown and described.

DESCRIPTION

FIG. 1 is a front perspective view showing our new fastening device design in the environment of use of the design.

FIG. 2 is a rear perspective view thereof in the environment of use of the design;

FIG. 3 is a front plan view thereof;

FIG. 4 is a rear plan view thereof;

FIG. 5 is a left side view thereof;

FIG. 6 is a top view thereof; and,

FIG. 7 is a bottom view thereof.

Dashed or otherwise broken lines are used for illustrative purposes only to give environmental context to the claimed design and do not form any part of the claimed design.
